UNITED STATES PATENT OFFICE.

CHARLES B. ROYAL, OF CHICAGO, ILLINOIS.

OILING DEVICE FOR JOURNAL BOXES.

Application filed February 7, 1924. Serial No. 691,151.

To all whom it may concern:

Be it known that I, CHARLES B. ROYAL, a citizen of the United States, residing at Chicago, in the county of Cook and State 5 of Illinois, have invented a new and useful Improvement in Oiling Devices for Journal Boxes, of which the following is a specification.

This invention relates to means for lubricating journal boxes such as are used 10 on trucks of railway cars and the like.

The space beneath the journal and within the journal box is commonly filled with waste and oil is poured over this. This 15 oil is carried to the journal by capillary attraction. For many reasons this method of oiling the journal is very unsatisfactory.

The primary object of this invention is 20 to provide a suitable means for conveying oil from the pocket in the bottom of the journal box to the journal as the latter rotates.

This and other objects are accomplished 25 by this invention which is fully described in the following specification and shown in the accompanying drawings in which:

Figure 1 is a longitudinal section through 30 the journal box on the line 1—1 of Fig. 2; Fig. 2 is a transverse section on the line 2—2 of Fig. 1; and

Fig. 3 is a partial developed view of the flexible oiling member.

The invention is applied to a standard 35 journal box having a housing 10, such as is commonly used on the trucks of railway cars and the like. The housing 10 surrounds the journal 11 on the end of the shaft 12, the journal supporting suitable 40 bearing members 13 and 14 such as are commonly employed for this purpose.

The lower part of the housing 10 has 45 a bottom 15 providing a pocket 16 beneath the journal 11. Within the space I have provided an oiling device comprising a flexible member made up of a series of felt strips 17 secured in any suitable manner as by stitching to an endless belt 18 which may be made of any suitable material 50 such as cotton fabric.

This flexible member passes over two rollers 19 and 20 which are journalled upon pins 21 and 22 which in turn are carried by crossed bars 23 and 24 which are pivotally connected near their center, the lower 55 end bearing upon the housing bottom 15.

These bars are connected by pins 25 and 26 upon which is mounted a roller 27 which has a grooved or spiked surface 28, the latter bearing upon the inner surface of the 60 flexible member at the bottom of its swing. An operating lever 29 is connected to the pin 25.

A tension spring 30 at each end of the bearing connects the bars 23 and 24 and 65 serves to force the rollers 19 and 20 toward each other thereby pressing the felt strips 17 into contact with the journal.

In addition to the action already described, oil is fed to the journal by the 70 flexible member which acts as a wick, conveying oil by capillary attraction from the body of oil in the bottom of the journal box.

The method of operation of the device 75 is as follows: As the axle turns there is a small amount of friction between the journal 11 and felt strips 17 which causes the flexible member to gradually move in the direction of the surface of the journal with 80 which it is in contact, but at a very much slower rate of speed. As this occurs the felt strips 17 pick up oil from the bottom of the journal box and carry it around into contact with the journal, thereby thoroughly lubricating the same. In case, however, it is desired that oil shall be quickly 85 fed to the bearing, particularly when the bearing has remained stationary for a long period of time, the operator raises the housing cover 10^a and reaches in through the front opening, moves the lever 29, thereby causing the flexible member to be moved, thus bringing a fresh supply of oil into contact with the journal.

While I have shown and described certain embodiments of my invention, it is to be understood that it is capable of many modifications. Changes therefore in the construction and arrangement may be made 100 without departing from the spirit and scope of the invention as disclosed in the appended claims, in which it is my intention to claim all novelty inherent in my invention as broadly as possible in view of 105 the prior art.

I claim:

1. In a railway journal box, in combination, a journal having bearing upon its upper surface, a bearing housing surrounding said journal and having an oil pocket beneath the same, a flexible member adapt-

ed to dip into said oil and to have frictional engagement with said journal to cause said flexible member to move to carry oil to said journal, said flexible member comprising a series of parallel strips of felt secured to an endless fabric belt.

2. In a railway journal box, in combination, a journal having bearing upon its upper surface, a bearing housing surrounding said journal and having an oil pocket beneath the same, a flexible member adapted to dip into said oil and to have frictional engagement with said journal to cause said flexible member to move to carry oil to said journal, said flexible member comprising a series of parallel strips of felt secured to an endless fabric belt, and means for mov-

ing said flexible member independently of the movement of the journal.

3. In a railway journal box, in combination, a journal having bearing upon its upper surface, a bearing housing surrounding said journal and having an oil pocket beneath the same, a flexible member adapted to dip into said oil and to have frictional engagement with said journal to cause said flexible member to move to carry oil to said journal, said flexible member comprising a series of parallel strips of felt secured to an endless fabric belt, and a sprocket engaging said flexible member for independently moving said member.

CHARLES B. ROYAL.
